(57) **CLAIM**

The ornamental design for a power socket, as shown and described.

DESCRIPTION

FIG. 1 is a perspective view of the power socket of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

In FIGS. 3 and 7, the broken lines are for the purposes of illustrating environment only and form no part of claimed design.
